UNITED STATES PATENT OFFICE.

CLIFTON R. HOLMES, OF MONTGOMERY, MICHIGAN.

TIMER.

1,250,105.

Specification of Letters Patent. Patented Dec. 11, 1917.

Application filed November 6, 1916. Serial No. 129,844.

To all whom it may concern:

Be it known that I, CLIFTON R. HOLMES, a citizen of the United States, residing at Montgomery, in the county of Hillsdale and 5 State of Michigan, have invented certain new and useful Improvements in Timers; and I do declare the following to be a full, clear, and exact description of the invention, such as will enable others skilled in the art 10 to which it appertains to make and use the same.

My invention has for its object to improve upon the construction shown in my allowed U. S. patent application Serial No. 78,939, 15 filed February 17, 1916, the principal end in view being more simple and less expensive construction without sacrificing any advantages.

With the foregoing general object in view 20 the invention resides in certain novel features of construction and in unique combinations of parts to be hereinafter fully described and claimed, the descriptive matter being supplemented by the accompanying 25 drawing which constitutes a part of this application and in which:

Figure 1 is a vertical longitudinal section of the improved timer;

Figs. 2 and 3 are vertical transverse sections on the planes of the lines 2—2 and 30 3—3 of Fig. 1; and,

Fig. 4 is a perspective view of one of the ring supporting brackets.

In the drawings above briefly described 35 the numeral 1 designates a cylindrical casing having a closed end 2 which is preferably though not necessarily of conical formation, said casing being adapted to be supported in such a manner as to permit it to 40 turn upon its axis in the usual manner, an arm 3 being provided for the attachment of suitable operating means.

Positioned coaxially in the casing 1 is a 45 flat ring 5 of compressed fiber or other appropriate insulating material, said ring having formed therethrough a plurality of openings 5 whose axes are parallel to the axis of the casing, said openings equaling in number the number of cylinders of the 50 engine with which the timer is to be used.

A plurality of ring supporting brackets 6 are provided, said brackets being equal in number to the openings 5 for a purpose to appear. Each bracket 6 is preferably 55 formed of a single plate stamped from sheet metal and bent into L-shape, said brackets

having one of their arms 7 extending over one end of the openings 5 and secured in contact with one flat face of the ring 4 by screws 8 passing through said arms as 60 shown. The other arms 9 of the brackets 6 are parallel with the axis of the casing 1 and extend across the peripheral edge of the ring 4 in spaced relation thereto, being insulated from the curved wall of said casing 65 by washers 10 or the like.

Binding posts 11 are insulated from the aforesaid curved wall of the casing 1 and pass therethrough and through the arms 9, whereby to effectively secure the brackets 6 70 in operative position and at the same time to provide means for connecting the current distributing wires with said brackets.

Contact plugs 12 are seated immovably 75 in the openings 5 with their outer ends flush with the flat face of the ring 4 opposite that to which the arms 7 are secured, electrical connectors 13 in the form of coiled springs being housed within said openings 5 between the plugs and arms in question 80 and in contact with both.

The hub 14 of a disk 15 is keyed on the timer shaft 16 which projects into the casing 1, said disk 15 carrying a socket 17 which opens toward the ring 4, said socket 85 receiving slidably therein a brush 18 to whose inner end a coiled spring 19 is secured in any preferred manner at one of its ends, the other end of said spring being secured to the disk. The brush 18 is adapted 90 to successively contact with the plugs 12 to complete the circuit of the spark plugs of the engine and travels between said plugs upon the ring 4.

It may here be stated that the casing 1 95 will by preference be of aluminum, the brackets 6 of brass and the plugs 12 and brush 18 of carbon. The materials used, however, are unimportant as long as they be appropriate. Similarly the exact features of 100 construction employed may vary within the scope of the invention as claimed without sacrificing any principal advantages. I prefer, however, to make the ring 5 of red fiber and the brush 18 of carbon, since these 105 parts become glazed by continual sliding one upon the other, and thus reduce friction and wear to a minimum without the use of grease in the casing 1.

I claim:

1. A timer comprising a cylindrical casing, a flat ring of insulating material posi-

tioned coaxially in said casing and out of contact therewith, said ring having a plurality of openings therethrough with their axes parallel with the axis of the casing, L-shaped ring-supporting brackets having one arm disposed over one end of the aforesaid openings and secured to one face of the ring, the other arms of said brackets being insulated from the curved wall of the casing, 5 binding posts insulated from said wall and passing therethrough and through the last named arms of the brackets to secure said brackets in position and at the same time to afford means for connecting distributing 10 wires thereto, contact plugs in the aforesaid openings and flush with the face of the ring opposite that to which the first named arms of the brackets are secured and a rotary brush operating over said last named face of the ring for successive contact with said 15 plugs.

2. A timer comprising a cylindrical casing, a flat ring of insulating material positioned coaxially in said casing and out of 20 contact therewith, said ring having formed therethrough a plurality of openings whose axes are parallel with the axis of the casing, an equal plurality of ring-supporting brackets formed of sheet metal plates bent 25 into L-shape, said brackets having one of 30

their arms disposed in contact with one flat face of the ring and extending over one end of the aforesaid openings, screws passing through these ends of the brackets and into the ring to secure the latter rigidly thereto, the other arms of the brackets being parallel with the axis of the casing, extending across the outer edge of the ring and being insulated from the curved wall of said casing, binding posts also insulated from said wall and passing therethrough and through the last named arms of the brackets, contact plugs fitting immovably in the aforesaid openings with one end flush with the flat face of the ring opposite that to which the first named arms of the brackets are secured, electrical connectors in the form of coiled springs disposed in said openings in contact with these arms and the plugs, and a rotary brush operating over said last named face 40 of the ring for successive contact with said plugs.

In testimony whereof I have hereunto set my hand in the presence of two subscribing witnesses.

CLIFTON R. HOLMES.
